UNITED STATES PATENT OFFICE.

GEORGE C. MURRAY, OF CHICAGO, ILLINOIS.

DRAFT-GEAR YOKE.

1,391,203.

Specification of Letters Patent. Patented Sept. 20, 1921.

Application filed December 11, 1919. Serial No. 344,003.

To all whom it may concern:

Be it known that I, GEORGE C. MURRAY, a citizen of the United States, residing at Chicago, in the county of Cook and State of Illinois, have invented certain new and useful Improvements in Draft-Gear Yokes, of which the following is a specification.

This invention relates to a draft gear yoke for railway cars and its purpose is to provide a yoke having improved means for securing the coupler butt therein.

The principal object of the invention is to provide a shouldered coupler butt in combination with a yoke having a movable block adapted to be tilted into a position wherein it engages one of the shoulders of the butt. A further object is to provide a yoke having a movable block adapted to lie in a substantially horizontal position during the insertion of the coupler butt into the yoke and to be tilted forwardly about its lower edge after the coupler has been inserted, improved means being provided for retaining the block in its upright position wherein it engages one of the shoulders of the butt. Other objects relate to various other features of construction and arrangement which will be described more fully hereinafter.

The nature of the invention will be understood from the following specification taken with the accompanying drawings in which one embodiment is illustrated.

In the drawings—

Figure 1 shows a side elevation of the coupler butt and yoke with the forward part of the yoke illustrated in vertical section on the line 1—1 of Fig. 2;

Fig. 2 is a vertical section through a shank of the coupler showing a front elevation of the yoke and coupler butt;

Fig. 3 is a sectional view similar to that of Fig. 1 through the forward end of the yoke showing the position of the movable block during the insertion of the coupler butt;

Fig. 4 shows a horizontal section through the forward end of the yoke on the line 4—4 of Fig. 1 with the coupler butt removed;

Fig. 5 shows a horizontal sectional view through the forward end of the yoke through the line 5—5 of Fig. 3 with the coupler butt removed;

Fig. 6 shows an enlarged perspective view of the forward end of the lower wall of the yoke showing the means for supporting and guiding the movable block; and

Fig. 7 is a perspective view of the movable block.

The yoke 10 is provided with upper and lower arms 11 and 12, respectively, which are united at their rear ends by the integral wall 13. At their forward ends the arms 11 and 12 are united by integral side walls 14, thus forming a hood or closure at the forward end of the yoke. The upper arm 11 is provided at its forward end with an integrally formed flange or shoulder 15 which extends downwardly to engage the upper shoulder 16 of the coupler butt 17. The coupler butt 17 is adapted to rest at its rear end on the lower wall 12 of the yoke as shown at 18. From the part 18, the lower wall inclines downwardly as shown at 19 and is then directed forwardly as shown at 20, thus forming a depression 21 beneath the coupler butt. The part 20 of the lower wall terminates in a transverse shoulder 22 and this shoulder terminates at its ends in forwardly extending lugs or flanges 23 which are formed integrally with the side walls 14. The shoulder 22 and the lug 23 are adapted to coact with the movable block 25 which is adapted to engage the lower shoulder 26 of the coupler butt. This block is provided with a rounded lower edge 25^a which is adapted to rotate on the rounded surface formed on the lower wall at the lower edge of the shoulder 22 and the block increases in thickness toward its upper edge, as shown in Figs. 1 and 3.

During the insertion of the coupler butt into the yoke, the block 25 is adapted to rest in a substantially horizontal position on the part 20 of the lower wall, as illustrated in Fig. 3. The block 25 is provided at its upper edge with longitudinally extending ears or lugs 27 and when the block 25 is in its horizontal position, these ears are adapted to lie rearwardly of the curved ribs or guides 28 which are formed integrally with the side walls 14 and extend upwardly and forwardly from the part 20 of the lower wall. When inserting the coupler or drawbar butt into the yoke, the shank 17^a of the coupler or drawbar is tilted downwardly in order to pass the coupler butt beneath the shoulder 15 and after the coupler butt has reached the rearward position illustrated by full lines in Fig. 3, the block 25 is tilted upwardly about its lower edge until the lugs 27 pass over the upper ends of the guides 28. During this tilting movement, the block

is lifted bodily from the lower wall of the yoke and after it has reached a position beyond the upper edges of the guides 28, the block drops into position between the lugs 5 23 and the forward edges 28 of the guides, with the lower edge of the block resting against the shoulder 22. The block is then held rigidly against movement and is secured in the proper position to coact with 10 the lower shoulder of the coupler butt when the latter is in its normal forward position. When the coupler butt moves rearwardly during the compression of the draft gear, the ribs or guides 28 will prevent the block 15 from tilting downwardly to its lower position. For the purpose of facilitating the movement of the block, the portion 20 of the lower wall is provided with an aperture 29 into which a suitable tool may be inserted 20 to engage a centrally located depression 30 which is formed in the under side of the block. An upward push on the tool inserted through the aperture 29 will lift the block upwardly through the guide ribs 28. 25 In order to prevent the rearward movement of the block 25 when it is being pushed upwardly, longitudinal lugs 32 are preferably formed on the lower edges of the block and these lugs project beyond the ribs 28 so that 30 they are adapted to engage the forward sides of the ribs during the tilting of the block. When the coupler butt is to be removed from the yoke, it is first displaced rearwardly and then the block is elevated in the reverse direction 35 over the ribs 28 by means of a tool engaging a depression 31 which is formed in the forward or upper side of the block. This construction has the advantage that the block is securely held in position by parts 40 that are formed integrally with the yoke so that it is unnecessary to employ any form of removable device for securing the block in position. After the coupler butt has been inserted and at all times during the operation 45 of the draft gear, the coupler butt is supported entirely by the lower wall of the yoke upon which it rests directly so that all strains are removed from the block 25 except the forward force imparted thereto by 50 the lower shoulder of the coupler butt.

Although I have shown and described one form of the invention for purposes of illustration, it will be understood that it may be constructed in various other forms without departing from the scope of the appended claims.

I claim:-

1. The combination with a yoke having upper and lower arms and a hooded forward end, of a drawbar having a shouldered butt adapted to be received within said hooded end, said lower arm being adapted to engage and support said butt, means carried by said yoke for engaging one shoulder of said butt,

65 a movable block being adapted to be tilted upwardly and forwardly about its lower edge into position to engage the other shoulder of said butt after the latter has been inserted in said yoke, and means formed integrally with said yoke for holding said 70 block in said last-named position after it has been tilted.

2. The combination with a yoke having upper and lower arms and a hooded forward end, of a drawbar having a shouldered butt 75 adapted to be received within said hooded end, said lower arm having a part adapted to engage and support said butt, means carried by said yoke for engaging one shoulder of said butt, said yoke being provided with 80 a lug adjacent the other shoulder of said butt, a movable block adapted to be tilted forwardly of said yoke to engage said other shoulder of said butt after said butt has been displaced rearwardly on said lower arm, 85 and means in addition to said lower wall formed integrally with said yoke to hold said block in position against said lug.

3. The combination with a yoke having upper and lower arms and a hooded forward end, of a drawbar having a shouldered butt adapted to be received within said hooded end, means carried by said hooded end to engage one shoulder of said butt, a 90 movable block adapted to be tilted into position to engage the other shoulder of said butt, and means carried by said yoke for guiding said block in its tilting movement and preventing the reverse tilting thereof. 95

4. The combination with a yoke having 100 upper and lower arms and a hooded forward end, of a drawbar having a shouldered butt adapted to be received within said hooded end, means carried by said hooded end to engage one shoulder of said butt, a movable 105 block adapted to be tilted into position to engage the other shoulder of said butt, and means carried by said yoke for guiding said block in its tilting movement, said last-named means being adapted to hold said 110 block in said position engaging said other shoulder of said butt.

5. The combination with a yoke having upper and lower arms and a hooded forward end, of a drawbar having a shouldered butt 115 adapted to be received within said hooded end, means carried by said hooded end to engage one shoulder of said butt, and a movable block adapted to be tilted into position to engage the other shoulder of said 120 butt, said block being capable of being tilted to inoperative position within said hooded end to release said butt only after the latter has been displaced rearwardly in said yoke, said yoke having a part over which a part 125 of said block must be lifted in moving from one position to the other.

6. The combination with a yoke having

- upper and lower arms and a hooded forward end, of a drawbar having a shouldered butt adapted to be received within said hooded end, means carried by said hooded end to 5 engage one shoulder of said butt, and a movable block adapted to be tilted into position to engage the other shoulder of said butt, said block being capable of being tilted to inoperative position to release said butt only 10 after the latter has been displaced rearwardly in said yoke, said yoke having a part over which a part of said block must be lifted in moving from one position to the other, said block being located entirely in 15 front of said butt when engaging said other shoulder, said butt being supported entirely by the lower arm of said yoke.
7. The combination with a yoke having upper and lower arms and a hooded forward end, of a drawbar provided with a shouldered butt adapted to be received within said hooded end, a flange carried at the forward end of said upper arm to engage the upper shoulder of said butt, another flange carried 25 at the forward end of the lower arm of said yoke, a movable block seated within said forward end and adapted to be tilted about its lower edge to a position against said last-named flange to engage the lower shoulder 30 of said butt, a projecting part carried by said yoke, and means carried by said block and adapted to be passed over said projection during the tilting of said block.
8. The combination with a yoke having upper and lower arms and a hooded forward end, of a drawbar provided with a shouldered butt adapted to be received within said hooded end, a flange carried at the forward end of said upper arm to engage the upper 35 shoulder of said butt, another flange carried at the forward end of the lower arm of said yoke, a movable block seated within said forward end and adapted to be tilted about its lower edge to a position against said last-named flange to engage the lower shoulder 40 of said butt, a projecting part carried by said yoke, and means carried by said block and adapted to be passed over said projection during the tilting of said block, said 45 block being adapted to seat between said last-named flange and said projecting part when it is in position to engage the lower shoulder of said butt.
9. The combination with a yoke having upper and lower arms and a hooded forward end, of a drawbar having a shouldered butt adapted to be received within said hooded end, a shoulder carried by said upper arm to engage the upper shoulder of said butt, 50 another shoulder carried at the forward end of said lower arm, a movable block adapted to rest on said lower arm behind said second-named shoulder during the insertion of said butt into said yoke, said block being 55 capable of being tilted upwardly to a position against said second-named shoulder after said butt has been displaced rearwardly in said yoke, projecting parts carried by the side walls of said yoke, and projecting lugs carried by said block and adapted to pass 60 over said projecting parts in moving said block to butt-engaging position.
10. The combination with a yoke having upper and lower arms and side walls forming a hooded forward end, of a drawbar having a shouldered butt, a flange carried at the forward end of said upper arm to engage the upper shoulder of said butt, another flange carried at the end of said lower arm, lugs projecting upwardly against said 65 side walls at the ends of said second-named flange, other projecting parts formed integrally with said side walls rearwardly of said lugs, and a movable block adapted to seat between said projecting parts and said lugs 70 and to engage said second-named flange, said block being adapted to engage the lower shoulder of said butt.
11. The combination with a yoke having upper and lower arms and side walls forming a hooded forward end, of a drawbar having a shouldered butt, a flange carried at the forward end of said upper arm to engage the upper shoulder of said butt, another flange carried at the end of said lower arm, lugs 75 projecting upwardly against said side walls at the ends of said second-named flange, ribs formed on the side walls of said yoke rearwardly of said lugs, and a movable block adapted to rest on said lower arm and to 80 underlie said butt during the insertion of the butt into said yoke, said block having longitudinally projecting lugs located rearwardly of said ribs when said block is resting on said lower arm, said block being 85 adapted to be tilted upwardly and forwardly to a position wherein it seats against said second-named flange and said first-named lugs.
12. The combination with a yoke having upper and lower arms and side walls forming a hooded forward end, of a drawbar having a shouldered butt, a flange carried at the forward end of said upper arm to engage the upper shoulder of said butt, another 90 flange carried at the end of said lower arm, lugs projecting upwardly against said side walls at the ends of said second-named flange, ribs formed on the side walls of said flange, ribs formed on the side walls of said yoke rearwardly of said lugs, a movable 95 block adapted to rest on said lower arm and to underlie said butt during the insertion of the butt into said yoke, said block having longitudinally projecting lugs located rearwardly of said ribs when said block is resting on said lower arm, said block being 100 adapted to be tilted upwardly and forwardly to a position wherein it seats against said second-named flange and said first-named lugs.
13. The combination with a yoke having upper and lower arms and side walls forming a hooded forward end, of a drawbar having a shouldered butt, a flange carried at the forward end of said upper arm to engage the upper shoulder of said butt, another 105 flange carried at the end of said lower arm, lugs projecting upwardly against said side walls at the ends of said second-named flange, ribs formed on the side walls of said flange, ribs formed on the side walls of said yoke rearwardly of said lugs, a movable 110 block adapted to rest on said lower arm and to underlie said butt during the insertion of the butt into said yoke, said block having longitudinally projecting lugs located rearwardly of said ribs when said block is resting on said lower arm, said block being 115 adapted to be tilted upwardly and forwardly to a position wherein it seats against said second-named flange and said first-named lugs.
14. The combination with a yoke having upper and lower arms and side walls forming a hooded forward end, of a drawbar having a shouldered butt, a flange carried at the forward end of said upper arm to engage the upper shoulder of said butt, another 120 flange carried at the end of said lower arm, lugs projecting upwardly against said side walls at the ends of said second-named flange, ribs formed on the side walls of said flange, ribs formed on the side walls of said yoke rearwardly of said lugs, a movable 125 block adapted to rest on said lower arm and to underlie said butt during the insertion of the butt into said yoke, said block having longitudinally projecting lugs located rearwardly of said ribs when said block is resting on said lower arm, said block being adapted to be tilted upwardly and forwardly to a position wherein it seats against said second-named flange and said first-named lugs.

named flange and said first-named lugs, the projecting lugs on said block being adapted to drop downwardly between the ends of said ribs and said first-named lugs when said block reaches its forward position.

13. The combination with a yoke having upper and lower arms and side walls forming a hooded forward end, of a drawbar having a shouldered butt, a flange carried at the 10 forward end of said upper arm to engage the upper shoulder of said butt, a second flange carried at the forward end of said lower arm, a movable block adapted to rest on the lower arm of said yoke rearwardly of 15 said second-named flange during the insertion of said butt into said yoke, ribs formed on the side walls of said yoke rearwardly of

said second-named flange and at the ends of said block, and lugs formed on the ends of said block and overlapping said ribs rearwardly thereof, said block being adapted to be tilted upwardly and forwardly about its lower edge until said lugs pass over the upper ends of said ribs, said block being adapted to drop downwardly to a position wherein its forward face seats against said second-named flange and its rearward face seats against the forward ends of said ribs, said block in said last-named position being adapted to engage the lower shoulder of said butt. 20 25 30

In testimony whereof, I have subscribed my name.

GEORGE C. MURRAY.
